UNITED STATES PATENT OFFICE.

ISAAC H. CONGDON, OF OMAHA, NEBRASKA.

CAR-BRAKE.

SPECIFICATION forming part of Letters Patent No. 314,225, dated March 24, 1885.

Application filed February 9, 1885. (No model.)

To all whom it may concern:

Be it known that I, ISAAC H. CONGDON, a citizen of the United States, residing at Omaha, in the county of Douglas and State of Nebraska, have invented certain new and useful Improvements in Brakes for Trucks of Railway-Cars, of which the following is a specification, reference being had therein to the accompanying drawings, in which--

10 Figure 1 is a plan of a car provided with brake-levers according to my invention; Fig. 2, a side elevation of the same; Fig. 3, an end view of the same. Fig. 4 shows the equalizing rods, levers, &c., all connected as in Fig. 1, but detached from the car. Fig. 5 shows the equalizing-levers in plan and side view and upon a larger scale.

15 This invention has relation to hand-brakes for railway freight-cars, or it may be for street-cars and like conveyances; and the object of the invention is to so divide the power applied at the brake-wheel at one end of the car as to bring equal pressure on both trucks of said cars. The levers or equalizer by which 20 this is accomplished are simple and inexpensive, and so arranged that the brake-levers now on cars can still be used. Another object attained by the equalizer is that by small 25 variations of construction power applied to 30 brakes of trucks can be increased or diminished without changing other parts of the brake-rig.

The equalizer is composed of the levers A and B, held together about the middle of their 35 length by a rivet or bolt, C, upon which they are crossed and can rock one above the other, like the blades of a pair of scissors.

To attach the equalizer to a car, a bolt is passed through one end of the lever A at a, 40 (or thumb end of scissors,) and said bolt is secured to the tie-plank D or to the sills F, as most convenient, according to the construction of the car, &c., and becomes a pivot for the equalizer to hang and swing upon. Having 45 attached the equalizer to the bottom of the car, the brake-rods are connected therewith.

To the lever B at b (corresponding with the finger end of scissors) is hooked the rod h, which has its opposite end connected to the 50 brake-staff S. To the end or point of the lever A and a', the rod i is secured, while to the end or point b' of the lever B the rod j is

fastened. These rods are connected with the brake-levers K and L, respectively. (See Figs. 1, 2, and 4.) Chains N N with ring at lower 55 end are suspended from the bottom of the car-body and carry the connecting-rods and prevent undue sag of the same.

In applying the brakes, as the brake-staff is turned from left to right, and the chain w 60 is wound around the same, the rod h is drawn, as indicated by the arrow, Fig. 4, and causes the lever B to move on the rivet C as a center, pulling the rod j and setting the brakes on one pair of trucks, while at the same time the 65 lever A moves on the center a and sets the brakes on the other truck; or the lever A may move around the center a and draw upon the rod i without affecting the rod j; or the lever B or the center C may draw upon the rod j 70 without affecting the rod i. Now, if by reason of unequal thickness of brake-shoes, untrue length of brake-rods, &c., the brakes on one truck are brought in contact with the 75 wheels sooner than the brakes on the other trucks, the inequality would be taken up by the lever A drawing upon the rod i, or the lever B drawing upon the rod j, as the case may be, till all the brakes come in contact with the wheels.

If wished, the leverage can be increased or diminished by altering the relative lengths of the ends of the levers of equalizer, as in any system of levers.

Formerly brakes were applied to the wheels 85 of but one truck of railroad-cars, which, with the small cars used and light loads then carried, was found sufficient; but within a few years size, and consequently weight, of freight-car bodies has been greatly increased, while 90 the carrying tonnage has nearly or quite doubled, and is ever increasing. This, together with high rate of speed at which many freight-trains are now run, makes the use of brakes upon all wheels of the car almost indispensable for safety.

95 Many cars have been fitted with double brakes, but with connections such that a pull is applied rigidly from one truck to the other and without equalization. When thus connected, if the brake-shoes differ in thickness, if one brake-beam is hung higher or lower than another, so that shoes have more or less travel before striking the circumference of

wheels, or if any of the connecting rods or levers are slightly long or short, or from warping of brake-beams, &c., the brake-shoes of one truck are brought in contact with wheels before those of the other, the braking-power is entirely expended on such wheels and will continue to be till the brake-shoes are worn enough to make up for untrue length of rods, &c., by which time it is generally necessary to renew them, and renewal results in a repetition of former conditions. Now, while this wear is going on pressure intended for both trucks is being applied to but one, causing the wheels to slide and rendering them useless. By the use of my improved equalizer these difficulties are entirely obviated.

Having now described my invention and its practical application, I claim—

1. The combination of the levers A and B, pivoted one above the other, (like the blades of a pair of scissors,) one of said levers having one end pivoted to the car and the other end

connected to the brake-lever at one end of the car, and the other lever having one end connected to the brake-staff and the opposite end secured to a brake-lever adjacent to said brake-staff, substantially as and for the purpose described.

2. The combination of the frame of a car, the crossed levers A B, pivoted together about the middle of their length, the rod *i* and brake-lever K at one end, the rod *j* and brake-lever L at the other, with the rod *h*, connected to the cross-levers at one end and to the brake-staff at the other, whereby tension from a brake-staff upon one rod is evenly divided and equalized upon two trucks of a car, substantially as described.

In testimony whereof I affix my signature in presence of two witnesses.

ISAAC H. CONGDON.
